UNITED STATES PATENT OFFICE.

JOHN GRAHAM, OF IBROX, GLASGOW, SCOTLAND.

RAISING AND LOWERING GEAR FOR SHIPS' BOATS.

1,099,645.

Specification of Letters Patent.

Patented June 9, 1914.

Application filed June 9, 1913. Serial No. 772,479.

To all whom it may concern:

Be it known that I, JOHN GRAHAM, a citizen of the United States of America, residing at Ibrox, Glasgow, Scotland, have invented certain new and useful Improvements in Raising and Lowering Gear for Ships' Boats, of which the following is a specification.

This invention relates to boat raising and lowering gear of the class in which a single davit is employed said davit turning about a vertical axis and having winding gear thereon preferably adapted to be operated manually.

Under the present invention instead of having a single rope which is wound upon a drum operated by gearing and provided with a hand operated brake, I employ a chain which is arranged to pass over a chain wheel and be actuated thereby and has one end attached to the davit structure while the other end is adapted to be paid into or out of the lower end of the davit which is made hollow so as to form a suitable chain receiving space or locker. Preferably, the chain is arranged to pass over guide pulleys in the upper part of the davit to the chain wheel aforesaid which is on a spindle carried on the davit and driven by a spur or other gear from a driving shaft operated by a crank handle or handles. From the chain wheel the chain passes up and over a second chain wheel and then downward into the interior of the davit. The second chain wheel is preferably provided with a guard or muzzle suitably arranged to prevent the chain jumping on the wheel.

In connection with the winding gear, I employ a self sustaining brake of the differential pattern and which is adapted automatically to hold the boat in any position during the raising or lowering operation should the operators let go the handles or be washed away from their posts.

The invention also comprises other novel features hereinafter described and pointed out in the claims.

A preferred form or embodiment of the invention is illustrated, by way of example, on the drawings appended hereto and forming part of this specification.

On the drawings: Figure 1 is a side view of the davit, showing a boat raised off the chocks ready for lowering. Fig. 2 is a detached side view to an enlarged scale of the winding and brake mechanism. Fig. 3 is a

view of the winding and brake mechanism as seen in the direction of the arrow *a* Fig. 2. Fig. 4 is an elevation and Fig. 5 a plan of one form of locking device for the davit. Fig. 6 is a plan of a modified form of davit locking device. Fig. 7 is a view showing the boat sling attached to a boat and Figs. 8 and 9 are detail views of a part of the boat sling. Fig. 10 is an enlarged view of the hook 59.

In carrying the invention into effect or practice in the manner illustrated by the accompanying drawings, the davit 10 is built up of steel plates 70 strengthened by angle irons 71, bent to the necessary shape and united by metal lattice work 72 and is provided with a pair of side cheeks or brackets 11 in which is rotatably mounted a winch shaft 12 having securely mounted thereon, between the cheeks 11, a pinion 13 and, external of the cheeks 11, a pair of winch handles 14. The pinion 13 meshes with a second pinion 15 rotatably carried by a pin 16 secured to, and projecting inwardly from, the right hand cheek 11. A shaft 17 is rotatably carried by the cheeks 11 and has securely mounted thereon a spur wheel 18, a pinion 19 and a brake drum 20. The spur wheel 18 meshes with the pinion 15 and the pinion 19 meshes with a spur wheel 21 on a pulley shaft 22 which is rotatably mounted in the cheeks 11 and carries, securely mounted thereon, a chain driving pulley 23. The brake drum 20 is embraced by the brake band 24 of a self-sustaining brake of the differential type and which may be adjusted or controlled by means of a screwed spindle 25 mounted in bearing brackets 26 attached to the cheeks 11, a hand wheel 27 being provided for turning same.

Guide pulleys 28 and 29 and an idle pulley 30 are provided in suitable positions on the davit 10 and a chain 31, secured at one end to the davit at 32 and passing around the pulley 34 of a movable fall 33, is passed over the guide pulley 29, guide pulleys 28, chain driving pulley 23, idle pulley 30 and the free end thereof passed into a chain stowage or locker 35 formed by the hollow lower end of the davit. The guide pulleys 28 are preferably plain grooved pulleys while the idle pulley 30 is a chain pulley and is also preferably provided with a guard or muzzle 63 to prevent the chain jumping thereon. Of course, any or all of the pulleys may be provided with a guard or muzzle if desired,

while bosses 62 are also preferably attached to the cheeks 11 at the places where the several shafts are journaled therein in order to provide a larger bearing surface.

5 For the purpose of preventing a boat swinging outward, when it is held suspended and the davit is being slewed, an arm 36 is pivotally mounted on the davit 10 and provided at its outer end with a pair of guides or brackets 37 adapted to engage the gunwale or other suitable part of the boat in such a manner as to allow a certain amount of movement therebetween, thereby holding the boat in position relatively to the davit 10 but allowing it, at the same time, a certain amount of lateral movement.

In order that the davit may be locked in position when desired there is securely mounted thereon a journal or annulus 38 provided with a lateral snug or projection 39 upon which are pivotally mounted, in brackets 40, pawls 41 adapted to engage holes 42 in the deck gland 43 through which the journal 38 passes. Arms 44 of a bifurcated link 45 may be pivotally secured to the pawls 41, said link being connected, at its upper end, with a lever 46 pivotally mounted on the davit 10.

A modified form of locking device is illustrated at Fig. 6, whereon the davit 10 is provided with a journal 38, gland 43 and lever 46 as aforesaid but in this case the snug or projection 39 is dispensed with and the holes 42 are replaced by radial slots 48. A pawl 47, pivotally mounted on the davit 10 or journal 38, is adapted to engage the slots 48 formed in the gland 43 and is connected to the pivoted lever 46 by a plain link 49. The lower end of the davit 10 is mounted in a 40 foot-step bearing 50 secured to a suitable part of the ship, in the usual or any suitable manner. With this davit, boats are slung by means of converging brackets 51 rigidly secured to the bottom of the boat and passing through eye brackets 52 secured to the seats 53. Each bracket is jointed, by means of a tumbler bolt 55, to one end of a swing link 54 whose other end is jointed to a rigid member or link 56 which latter is again connected, by means of a flexible member 57 with an eye or link 58 with which the hook 59 of the fall 33 of the davit is connected. Each swing link 54 has an arm or extension 60 thereon provided with a lateral guide eye 55 or hook 61 of such shape as to allow the rigid member 56, which passes therethrough, a small amount of lateral play. With this arrangement when a boat is launched and the slinging tackle disconnected from the davit 60 hook the rigid members or links 56 are held in place by the eye or hook 61 of the extension 60 until the tumbler bolts 55 are removed, thus preventing any injury to passengers owing to the fall of the slinging tackle 65 when it is disconnected from the davit.

When it is desired to launch a boat the boat tackle is secured in position and the davit slewed until the link 58 can be passed over the hook 59. The davit is then preferably locked by means of one of the hereinbefore described locking devices and the winch handles 14 turned in the proper direction. The turning of the handles 14 rotates the pinion 13 which, through the medium of the gearing hereinbefore described, rotates the chain driving pulley 23 which causes the chain 31 to raise the fall 33 and thereby lift the boat from the chocks, the excess chain, instead of being wound around a drum, being paid into the chain receptacle or locker 35. When the boat is raised sufficiently to clear the chocks, the davit is slewed outboard and, preferably, locked in position and the boat lowered. To raise and stow a boat the operation is, of course, the converse of that aforesaid. The hook 59 has a tongue 65 pivoted thereto, at 66, and provided with a heavier extension 67 this extension having a recess 68 with which a spring 69 on the body of the hook can engage. With this construction when the link 58 is inserted in the hook 59 the downward pull depresses the tongue 65 and brings the extension 67 into the position shown so that the spring 69 automatically engages the recess in the extension. Normally the action of the weighted extension 67 tends to raise the tongue and keep the hook open so that the link can readily be engaged, and when engaged the hook is closed by the pull of the link. Should, however, the action of a wave lift the boat sufficiently to take the pull off the link 58 the tongue cannot rise as the extension is held by the spring 69.

Should the operators leave their post, either when raising or lowering, and the weight of the boat commence to pay out the chain, the self-sustaining or differential brake at once acts and brings the boat to a standstill. In the case of raising and lowering a light boat instead of having the one end of the chain attached to the davit this end may simply hang down free and be provided with a hook (thus doing away with the bottom block at its lower end) a check being provided on the chain at a short distance from the hook to prevent it running through the pulley at the top of the davit.

If so desired the hoisting gear may, instead of being operated by hand, be operated by means of steam, hydraulic, electric or other power, the power being applied to the shaft 12.

Having now fully described my invention what I claim and desire to secure by Letters Patent is:—

1. A ship's davit hollow at its lower end, a chain wheel thereon, means for rotating said chain wheel, a second chain wheel, a guide pulley on the davit and a chain passing around the chain wheels and guide pul-

ley and having one end secured to the davit structure and the other end adapted to be paid into the hollow lower end of the davit.

2. A davit having its lower part adapted to be passed through the ship's deck and be rotatably mounted therein, said davit being hollow at its lower end, a chain wheel thereon, means for rotating said chain wheel, a second chain wheel, a guide pulley on the davit and a chain passing around the chain wheels and guide pulley and having one end secured to the davit structure and the other end adapted to be paid into the hollow lower end of the davit.

3. A ship's davit hollow at its lower end, a chain wheel thereon, means for rotating said chain wheel, a second chain wheel located above the level of the first chain wheel and directly above the hollow lower end of the davit, a guide pulley on the davit and a chain passing around the chain wheels and guide pulley and having one end secured to the davit structure and the other end adapted to be paid into the hollow lower end of the davit.

4. A davit having its lower part adapted to be passed through the ship's deck and be rotatably mounted therein, said davit being hollow at its lower end, means for locking the davit in desired positions, two chain wheels thereon one of which is located above the other, means for rotating one of said chain wheels, a guide pulley on the davit and a chain passing around the chain wheels and guide pulley and having one end secured to the davit structure and the other end adapted to be paid into the hollow lower end of the davit.

5. A ship's davit hollow at its lower end, two chain wheels thereon one of which is located above the level of the other, means for rotating one of said chain wheels, a guide pulley on the davit, a chain passing around both chain wheels and the guide pulley and having one end secured to the davit structure and the other end adapted to be paid into the hollow lower end of the davit and means for preventing the chain jumping off the upper chain wheel.

6. A ship's davit hollow at its lower end, two chain wheels thereon one of which is located above the level of the other, means for rotating one of said chain wheels, a guide pulley on the davit, a chain passing around both chain wheels and the guide pulley and having one end secured to the davit structure and the other end adapted to be paid into the hollow lower end of the davit, means for preventing the chain jumping off the upper chain wheel, a journal on the davit, a projection on said journal, pawls pivoted on said projection, a gland adapted to be secured to the ship's deck and within which the journal is adapted to rotate, a flange on said gland having holes therein

with which said pawls are adapted to engage and means for moving said pawls into or out of engagement with said holes.

7. A ship's davit hollow at its lower end, a chain wheel thereon, means for rotating said chain wheel, a second chain wheel, a guide pulley on the davit, a chain passing around the chain wheels and guide pulley and having one end secured to the davit structure and the other end adapted to be paid into the hollow lower end of the davit, and means whereby the movement of the chain is arrested should the winding mechanism be released when a weight is suspended from the chain.

8. A ship's davit hollow at its lower end, a chain wheel thereon, means for rotating said chain wheel, a second chain wheel located above the level of the first chain wheel and directly above the hollow lower end of the davit, a guide pulley on the davit and a chain passing around the chain wheels and guide pulley and having one end secured to the davit structure and the other end adapted to be paid vertically downward from said second chain wheel into the hollow lower end of the davit.

9. A ship's davit hollow and tapered at its lower end, a chain wheel thereon, means for rotating said chain wheel, a second chain wheel, a guide pulley on the davit and a chain passing around the chain wheels and guide pulley and having one end secured to the davit structure and the other end adapted to be paid into the hollow lower end of the davit.

10. A ship's davit made of an openwork structure and hollow throughout its length, guide pulleys arranged within the hollow davit, a chain wheel carried outside the hollow davit, a second chain wheel rotatably arranged within the hollow davit and above the level of the first chain wheel, a chain which is secured at its one end to the upper end of the davit and passes through the hollow davit and over the guide pulleys therein to and under the first chain wheel then up and over the second chain wheel and down into the interior of the lower end of the davit and means for rotating the first chain wheel.

11. A ship's davit made of an openwork structure and hollow throughout its length, guide pulleys arranged within the hollow davit, a chain wheel carried outside the hollow davit, a second chain wheel rotatably arranged within the hollow davit and above the level of the first chain wheel, a chain which is secured at its one end to the upper end of the davit and passes through the hollow davit and over the guide pulleys therein to and under the first chain wheel then up and over the second chain wheel and down into the interior of the lower end of the davit, means for rotating the first chain

wheel, a chain pulley block carried by the chain, said pulley block having a self locking hook thereon with pivoted extension therein and means for locking said extension.

12. A ship's davit made of an openwork structure and hollow throughout its length, guide pulleys arranged within the hollow davit, a chain wheel carried outside the hollow davit, a second chain wheel rotatably arranged within the hollow davit and above the level of the first chain wheel, a chain which is secured at its one end to the upper end of the davit and passes through the hollow davit and over the guide pulleys therein to and under the first chain wheel then up and over the second chain wheel and down into the interior of the lower end of the davit, means for rotating the first chain wheel, a chain pulley block carried by the chain, said pulley block having a self locking hook thereon, with pivoted extension therein, means for locking said ex-

25 tension, a pair of rigid members, means adapted to connect said members to said hook, a pair of brackets pivotally connected with said links and adapted to be secured to a boat and means for holding said rigid members in extended position when they are 30 disconnected from said hook.

13. Slinging tackle for use in connection with a davit, such as described, comprising converging brackets adapted to be secured to a boat, swing links pivotally secured to said 35 brackets and having arms or extensions provided with lateral guide eyes or hooks, rigid members pivotally secured to said swing links and passing through said guide eyes or hooks and means adapted to connect said 40 rigid members to the davit chain.

In testimony whereof I affix my signature in presence of two witnesses.

JOHN GRAHAM.
